(57) **CLAIM**

The ornamental design for a smart card interface, as shown and described.

DESCRIPTION

FIG. 1 is an environmental perspective view of a smart card interface;

FIG. 2 is an environmental top view thereof; and,

FIG. 3 is an enlarged top view thereof.

The broken line showing of a card upon which the claimed module is placed upon, is environmental and not claimed. Within the module, broken lines and unshaded portions contained within broken lines are not claimed.

1 Claim, 2 Drawing Sheets(56)
